DOOR CONTROL MECHANISM

Harry H. Marshall, Detroit, Mich.

Application September 30, 1932

Serial No. 635,627

1 Claim. (Cl. 268—62)

This invention relates to door control mechanism, and particularly to mechanisms for opening and closing garage doors.

The principal object of the present invention is to provide a new and improved door opening and closing mechanism to be applied to double and oppositely swinging doors found on garages.

Another object is to provide a new and improved device whereby two doors may be opened and closed simultaneously by the manual operation of operating cables, one operation unlocking, opening and locking open and another operation closing and securely locking the doors.

A further object of the present invention is to provide a locking device that will not only hold the doors in a locked position, but one that provides a locking mechanism that cannot be picked from the outside.

Another object is to provide an adjustable feature for opening and closing garage doors whereby the amount each door opens or closes may be varied to suit the requirement.

A still further object is to provide a new and improved device for opening and closing doors that does not necessitate the operator going into close or cramped quarters, the operating cables may be placed in any convenient part of the garage building.

Another object of the present invention is to provide a door opening and closing mechanism that locks the doors in an open position, thereby doing away with the necessity of placing stops or sticks against the doors to hold them in an open position while the operator drives the car into the garage.

A further object of the present invention is to provide a new and improved door opening and closing device that is installed upon the cross-brace of the door frame so that the same is conveniently out of the way.

The above and other objects of the present invention will appear more fully from the following more detailed description and by reference to the accompanying drawings forming a part hereof, wherein is shown, by way of example, a satisfactory commercial embodiment of the invention.

Fig. 1 is a top view taken on the line 2—2 of Fig. 3;

Fig. 2 is the same as Fig. 1, only showing the doors in an open position;

Fig. 3 is a view taken on the line 3—3 of Fig. 2;

Fig. 4 is a cross-section taken on the line 4—4 of Fig. 2;

Fig. 5 is a cross-section taken on the line 5—5 of Fig. 2;

Fig. 6 is an enlarged view of the locking device looking in the direction of the arrows shown in Fig. 3 with the doors in a closed position.

Referring now to the drawings:

The numeral 10 designates a piece of angle iron which is suitably secured to the cross beam of the door frame 11 (Fig. 3). Suitably secured to, and extending laterally therefrom is a plate 12. This plate or flange 12 extends inwardly of the cross-beam of the door frame, and the same has fulcrumed thereon the lever 14 by means of the pivot screw 13. The lever 14 has its outer extremity curved as at 15. A pair of levers 16, 16' are spaced equi-distant and in parallelism to the plate 12. The levers are fulcrumed on angle iron 10 by means of the pivot screws 17, 17'. Striker plates 18, 18' are formed on the outer ends of the levers 16, 16'. Rigidly secured to the lever 16 is a bar 19. Pivots secured to the bar 19 as at 20, and pivotally secured to the lever 14 as at 21 is a link 22. Pivots secured to the lever 14 as at 23, and pivotally secured at its other extremity to the lever 16' as at 24 is the link 25.

A pulley 26 is rotatably mounted on one end of arm 27, said arm 27 being rotatably mounted at its other end on pin 28 to the curved portion 15 of lever 14. Suitably secured to the outer extremity of arm 19 is an opening cable 29. Passed over pulley 26, and suitably secured to the arm 19 is the closing cable 30. Cables 29 and 30 pass over the pulley 31 (Fig. 1) and terminate as shown in Fig. 3. Suitable handles 31, 31' are provided to provide a grip for the operator.

Links 32, 32' are pivotally secured, one end to the levers 16, 16' by the pins 33, 33' and the other end to links of a pair of lazy tongs 34, 34' by the pins 35, 35'.

The outer link of the lazy tongs 34, 34' are pivotally connected to the swinging arms 36, 36' by means of the pins 37, 37'. The swinging arms 36, 36' are pivotally secured by the pins 38, 38' to the flanges 39, 39' (Fig. 2). The outer extremity of the arms 36, 36' have formed thereon turned down flanges 40, 40' (Figs. 2 and 3). The flanges are apertured to receive one end of the rods 41, 41' one end of said rods terminating in the brackets 42, 42' and are held in a rigid position by means of the pin 43 (Fig. 5). The outer extremity of the rods 110

41, 41' pass through the apertured brackets 44, 44' said brackets being rigidly secured to the doors as disclosed. Hooks 45, 45' are pivotally connected to the plates 44, 44' by means of 5 the pins 46, 46'. Links 47, 47' connect the rods 41, 41' with the hooks 45, 45' said links being pivotally connected to the end of the rods 41, 41' by means of the pins 48, 48' and to the hooks 45, 45' by means of the pins 49, 49'. Numerals 10 50, 50' represent the conventional double doors used on modern garages.

The manner in which the device operates is as follows:

It being assumed that the doors of the garage 15 are in a closed position, as shown most clearly in Fig. 1 of the drawings, and it is desired to open them, the operator grasps the handle 31, which has attached to it the cable 29, and pulls downwardly thereon. As shown in Fig. 3 of the 20 drawings, the cables and handles are positioned to one side of the doors, but if desired these cables and handles may be run to any convenient part of the garage building and the same efficient results will be obtained. This downward pull upon the handle 31 and cable 29 causes the arm 19, to which one end of the cable 29 is secured, to move to the position as shown in Fig. 2 of the drawings. This same force which is given to the cable 29 and arm 19 is also imparted to the link 22 which is pivotally connected to the arm 19 and lever 14 by means of the pivot pins 20, 21. When the arm 19 is moved to the position shown in Fig. 2, the lever 14 moves on its fulcrum 13 and assumes the 30 position as shown in Fig. 2. Link 25 connects lever 14 with lever 16' and this link assumes the position shown in Fig. 2 when the cable 29 has been pulled. Links 32, 32' are pivotally connected to the levers 16, 16' at 33, 33' and the other end of said links are pivotally connected to one end of the lazy tongs at 35, 35'. The outer extremity of the lazy tongs 34, 34' are pivotally connected to the arms 36, 36' at 37, 37'. The arms 36, 36' are slidably mounted on the 40 rods 41, 41', said rods being secured to the upper portion of the doors 50, 50'. When the doors begin their outward movement the hooks 45, 45' are released from the striker plates 18, 18' by means of the small links 47, 47' which are pivotally connected to the extremities of the rods 41, 41'. When the lazy tongs 34, 34' start to open, the outer extremity of said tongs being connected to the arms 36, 36' and said arms being slidably mounted on the rods 41, 41', the outer ends of the arms 36, 36' are abutting the plates 44, 44' as the doors swing outwardly the links 47, 47' cause the hooks 45, 45' to open and allow the doors to swing outwardly. When the doors have been opened to their full extent the 50 lazy tongs 34, 34' act as rigid braces and tend to hold the doors fully opened and in a locked position as shown in Fig. 2 of the drawings.

When it is desired to close the doors the handle 31' is pulled downwardly and as said handle is connected to the cable 30, and the cable 30 passes over the pulley 26, which pulley is attached to the lever 14, and the cable terminates in the arm 19, this force not only causes the arm 19 to move back to the position shown in 60 Fig. 1, but as the pulley through which the cable 30 passes, is attached to the lever 14, lever 14 is moved simultaneously with arm 19 back to the Fig. 1 position. This force is also imparted to links 32, 32' and in turn to the 70 lazy tongs 34, 34', and as the outer extremities

of said tongs are connected to arms 36, 36' and said arms to the rods 41, 41' the doors are swung inwardly. As the hooks 45, 45' come into contact with the striker plates 18, 18' the notched portion of said hooks 45, 45' passes over the plates and are locked in place, as shown best in Fig. 6 of the drawings. 80

If it is desired to have one door close before the other where doors overlap or have a wooden flange, this may be accomplished by setting the fulcrum of the lever 14 at the desired point on the plate 12. 85

I have provided a door opening, closing and locking means that will be cheap to manufacture and will bring the device within a price 90 range to suit the home owner. I have provided a mechanism that cannot be picked from the outside because the locking means are back from the door crack and down from the top sufficiently to make it impossible to reach the 95 locking means from the outside. My device also overcomes the old necessity of getting back of the car if quarters are close, the device can be operated from any point in the garage.

There will not be needed bricks or sticks to 100 hold the doors open in windy weather, nor will it be necessary to step outside of the garage to open locks or release gravity holders or catches. The doors may be opened or closed as quickly as the operator desires, which makes my device of 105 great advantage for fire engine houses where time counts. My device provides a good lock on each door, operates quickly, protects cars going in and coming out of garages as well as 110 protects the garage doors from ordinary abuse.

While I have described and illustrated a satisfactory installation that has proven highly successful in practical operation, it will be understood that the invention is not limited to specific constructional details shown and described, but that many changes, variations and modifications may be resorted to without departing from the principles of the invention. 115

I claim:

In a device of the class described including a 120 pair of oppositely hinged doors, a strip of iron fastened above the doors, a plate fastened to said strip of iron and extending laterally therefrom, a lever pivotally mounted on said plate, a pair of levers pivotally mounted, in parallelism to the plate, on said strip of iron, links connecting the lever mounted on the plate and the levers mounted on the strip of iron, striker plates mounted on the ends of the levers 125 mounted on the strip of iron, a pair of lazy-tongs, a pair of bars, the ends of which are pivotally mounted to the extremities of the strip of iron, links connecting the lazy-tongs with the levers mounted on the strip of iron, the other end of the lazy-tongs being pivotally mounted on the aforesaid bars, a pair of rods 130 held rigidly to the oppositely hinged doors, the outer extremities of the lazy-tongs being pivotally connected to the bars, a pair of locking hooks, links connecting the rods to said hooks, 135 an arm connected rigidly to one of the levers attached to the strip of iron, a pulley attached to one end of the lever attached to the plate, a pair of operating cables secured to the lever attached to the plate, and the arm attached to the lever which is pivotally mounted to the strip of iron. 140
